CLAIM

The ornamental design for a badge, as shown and described.

DESCRIPTION

FIG. 1 is a left front perspective view of the design of the badge;

FIG. 2 is a front elevational view thereof;

FIG. 3 is a rear elevational view thereof;

FIG. 4 is a right side elevational view with the left side being a mirror image thereof; and,

FIG. 5 is a top plan view thereof.

The broken lines shown are for illustrative purposes only and form no part of the design claimed.
